C. C. PORTER

BAKING PAD

Filed July 16, 1927

WITNESS: J. J. L. Wright

Charles C. Porter INVENTOR
BY Victor J. Evans

ATTORNEY

UNITED STATES PATENT OFFICE.

CHARLES C. PORTER, OF HARTFORD, CONNECTICUT.

BAKING PAD.

Application filed July 16, 1927. Serial No. 206,287.

My present invention has reference to a baking pad, that is, a pad upon which baking pans rest when in an oven to prevent the lower or bottom portion of the contents of 5 the pan from being burned during the cooking operation, the pan being also susceptible for use over the grate above the pan to likewise prevent the contents in the top of the pan from being burned or scorched.

10 An object is the provision of a pad or mat for this purpose which may be rolled, when not in use, to provide a small bundle for storage or for shipment and which is of a construction that will effectively perform its

15 function when in use.

A further object is the provision of a pad or mat for this purpose in which sheets of heat resisting material, such as asbestos or the like are held in spaced relation by a 20 reticulated member of corrugated formation, the pad being enclosed in a metal frame, and the end members of the frame being removable so that the pad, when the said end members are disassociated may be rolled 25 upon itself, the end members arranged in the roll and a finger ring, normally employed for manipulating the pad may be arranged around the pad for holding the same when in rolled condition.

30 To the attainment of the foregoing the invention consists in the improvement as hereinafter described and claimed.

In the drawings:

Figure 1 is a top plan view of a baking pan 35 in accordance with this invention.

Figure 2 is a sectional view on the line 2-2 of Figure 1.

Figure 3 is a sectional view on the line 3-3 of Figure 1.

40 Figure 4 is a detail view in perspective of a corner portion of the pad, with one of the frame elements withdrawn.

Figure 5 is a sectional view on the line 5-5 of Fig. 4.

45 Figure 6 is a perspective view showing the pad in rolled condition.

My improved baking pad includes spaced sheets 1 of heat resisting material, the sheets being constructed of asbestos or like material. Between these sheets 1 there is interposed a fine mesh wire 2 which is corrugated transversely throughout its length. The bulged portions of the wire hold the sheets 1 suitably spaced away from each other and 50 the wire mesh also serves as a means for preventing the free tearing of the sheets 1.

The mat thus provided is enclosed in a metal frame. The metal frame includes side and end members, each of a single strip of bendable metal, two of the interposed strips being bent into U-shaped formation and being clamped and if necessary crimped or indented along the sides and edges of the sheets. The members are indicated by the numeral 3 and each of the said members, 60 at or adjacent to their ends have sockets or depressions 4. The other and removable members of the frame are indicated by the numeral 5. The members 5, adjacent to their ends are indented from their outer faces 65 to provide inwardly projected cross sectionally rounded teats or lugs 6 to be received in the rounded depressions 4. In this manner it will be seen that the elements constituting the frame for the pad may be 70 readily associated or disconnected.

One of the frame members has associated therewith an eye 7 which is preferably pivotally or swingably secured on the said member, and this eye receives therethrough a 80 split ring 8. The ring is, of course, removable from the eye, it being merely necessary to bend the ends of the ring to insert the same in the eye or to remove the said ring therefrom. Normally the ring serves as a 85 finger hole whereby the mat may be inserted in an oven or removed therefrom but when the frame members 5 are removed and the mat is folded, as disclosed by Figure 6 of the drawings, the ring member is first disassociated from the eye and thereafter arranged around the roll. If desired, the ring member may be passed through the eye 7 when the mat is folded. When in folded condition the removable frame members 5 90 are inserted in the center of the roll as disclosed by Figure 6 of the drawings.

The construction and advantages of the improvement will be readily apparent to those skilled in the art to which the invention relates without further detailed description.

Having described the invention, I claim:

1. A baking pad as herein described comprising two sheets of heat resisting material, a corrugated sheet of mesh interposed between the sheets, a frame member connecting the ends and edges of the pad, and said frame member comprising oppositely disposed sections which are fixed to the pad and other sections which are removably secured to the pad and have an interengagement with the fixed members.

2. A baking pad as herein described, comprising two lapping sheets of heat resisting material, a corrugated mesh arranged between the sheets and spacing the same, a frame surrounding the pad, said frame comprising U-shaped metal members two of the opposite elements of which are compressed against the pad and having depressions ad-

jacent to their outer ends, the remaining U-shaped elements of the frame having inwardly directed teats to be received in the depressions of the fixed member of the frame and a split swivel ring removably secured to one of the frame members. 10

In testimony whereof I affix my signature.
CHARLES C. PORTER.
